UNITED STATES PATENT OFFICE.

GEORGE A. MACBETH, OF PITTSBURGH, PENNSYLVANIA.

GLASS-GRINDING APPARATUS.

1,114,160.

Specification of Letters Patent. Patented Oct. 20, 1914.

Application filed April 8, 1912. Serial No. 689,269.

To all whom it may concern:

Be it known that I, GEORGE A. MACBETH, a citizen of the United States, residing in Pittsburgh, in the county of Allegheny and State of Pennsylvania, have invented certain new and useful Improvements in Glass-Grinding Apparatus, of which the following is a specification.

This invention has reference to glass grinding apparatus and it has for its primary objects the provision of improved means for supplying abrasive material to the grinding surfaces, and the provision of improved means for maintaining the abrasive in proper suspended condition and directing a substantially continuous discharge or application of the abrasive at any place desired on the grinding surfaces. This together with such other objects as may herein-after appear or may be incidental to my invention I attain by means of a construction which I have illustrated in preferred form in the accompanying drawings wherein:—Figure 1 is a longitudinal section through a grinding mechanism showing the applications of my improved apparatus, Figure 2 is a plan view of the mechanism shown in Figure 1, and Figure 3 is an enlarged detail view of my improved agitating and directing mechanism. One of the chief objects of my invention is to provide a simple means for effectively agitating the abrasive mixture utilized in grinding glass articles so as to maintain it in proper suspended condition, and at the same time to secure a substantially continuous spray or discharge of the abrasive onto the grinding surfaces, at just the place where it may be desired or will be most effective.

Referring to Figures 1 and 2 of the drawing, it will be seen that I have diagrammatically illustrated a grinding wheel or table 5 which is provided with a grinding surface 6 adjacent the edge of which is an annular groove or channel 7 which is adapted to contain the mixture of water and abrasive material utilized in grinding the glass, the edge having an annular upstanding flange 7^a. The grinding table is mounted on the shaft 8 so as to rotate therewith, the shaft 8 being operated by any desired form of mechanism. The abrasive is discharged onto the table by means of the funnel or horn 9 which is supported in position in the channel 7 by means of the two-part arm or bracket 10 which is bolted

to the bracket 11 which may be integral with or secured to any desired part of the framework of the apparatus. In Figure 1 I have shown this bracket as being formed integrally with the upper bearing 12 of the shaft 8. The two parts of the bracket 10 are secured together by means of the bolt 13, the upper portion being slotted at 14 to permit of vertical adjustment of the funnel 9. The discharge spout 15 of the funnel 9 is bent substantially at right angles to the body of the funnel so as to secure a lateral discharge of the abrasive onto the table, or onto the glass article being ground. In the drawing I have illustrated the grinding of a lamp chimney 16 with the funnel arranged so that the abrasive will be discharged just in advance of the chimney.

In operation the rotation of the table 5 will drive or force a portion of the abrasive mixture into the funnel and secure a substantially continuous discharge of the same from the spout 15 onto the table and at the same time the abrasive mixture in the channel 7 will be thoroughly agitated and the sand or other abrasive material will be maintained in suspended condition. The device is simple and effective and secures uniformity of grinding.

Having thus described my invention and illustrated its use, what I claim as new and useful and desire to secure by Letters Patent is the following:

1. In glass grinding apparatus the combination with a rotary grinding table adapted to contain an abrasive mixture, a relatively stationary horn adapted to discharge a stream of abrasive onto the grinding surface of the table, and a supporting member for the horn adjustably mounted in such manner that the elevation and angular inclination of the horn may be varied.

2. In glass grinding apparatus, the combination with a rotating receptacle adapted to contain abrasive material, a grinding member rotatable with the receptacle, and a stationary conduit having a portion thereof lying in position in the said receptacle to scoop up the abrasive and discharge it onto the grinding member when the receptacle is rotated.

3. In glass grinding apparatus, the combination of a rotary member comprising a grinding disk and a channel about its periphery adapted to contain an abrasive material, and a conduit one end of which lies

in the channel in position to scoop up the abrasive when the said member is rotated, and the other end of which lies in position to discharge the abrasive scooped up onto the disk.

4. In combination, a rotary member comprising a grinding member and a receptacle surrounding the same, and a tapering horn having its large end lying in the receptacle and its small end in position to discharge onto the grinding member.

5. In combination, a rotary member com-

prising a grinding member and a receptacle surrounding the same, and a scoop having one part lying in the receptacle and another part in position to discharge onto the grinding table.

In testimony whereof I have hereunto signed my name in the presence of the two subscribed witnesses.

GEO. A. MACBETH.
